(57) **CLAIM**

The ornamental design for a slab, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a top plan view of a slab, showing our new design. The depicted surface of the slab is flat. The broken lines represent portions of the slab that form no part of the claimed design.
